Primary Examiner — Cathron C Brooks*Assistant Examiner* — Sharon S Oum*(74) Attorney, Agent, or Firm* — McGarry Bair PC(57) **CLAIM**

The ornamental design for a ceiling fan, as shown and described.

DESCRIPTION

FIG. 1 is a top perspective view of a ceiling fan according to my invention;

FIG. 2 is a bottom front perspective view of the ceiling fan of FIG. 1;

FIG. 3 is a top view of the ceiling fan of FIG. 1;

FIG. 4 is a bottom view of the ceiling fan of FIG. 1;

FIG. 5 is a front view of the ceiling fan of FIG. 1;

FIG. 6 is a rear view of the ceiling fan of FIG. 1;

FIG. 7 is a right view of the ceiling fan of FIG. 1; and,

FIG. 8 is a left view of the ceiling fan of FIG. 1.

The broken lines illustrate portions of the ceiling fan that form no part of the claimed design.

The ceiling fan blade is shown with a symbolic break in its length. The appearance of any portion of the ceiling fan blade between the break lines forms no part of the claimed design.
